US00D823419S

(12) United States Design Patent (10) Patent No.: US D823,419 S
(45) Date of Patent: * Jul. 17, 2018

(54) TENT

(71) Applicant: MANUFACTURE—ILES DU PONANT, Paris (FR)

(72) Inventor: Brice Ceccaldi, Paris (FR)

(73) Assignee: MANUFACTURE—ILES DU PONANT, Paris (FR)

() Term: 15 Years

(21) Appl. No.: 35/502,108

(22) Filed: Nov. 14, 2016

(80) Hague Agreement Data

Int. Filing Date: Nov. 14, 2016

Int. Reg. No.: DM/093689

Int. Reg. Date: Nov. 14, 2016

Int. Reg. Pub. Date: Dec. 16, 2016

(30) Foreign Application Priority Data

May 17, 2016 (FR) 20162598
May 17, 2016 (FR) 20162599

(51) LOC (11) Cl. 21-04

(52) U.S. Cl.

USPC D21/837

(58) Field of Classification Search

USPC D21/837
CPC E04H 15/24; E04B 7/14

See application file for complete search history.
